UNITED STATES PATENT OFFICE.

JAMES T. COWLEY, OF BOSTON, MASSACHUSETTS, ASSIGNOR TO THE LAMSON COMPANY, OF NEWARK, NEW JERSEY, A CORPORATION OF NEW JERSEY.

PNEUMATIC-DESPATCH-TUBE APPARATUS.

1,086,443.

Specification of Letters Patent.

Patented Feb. 10, 1914.

Application filed April 10, 1907. Serial No. 367,437.

To all whom it may concern:

Be it known that I, JAMES T. COWLEY, of Boston, in the county of Suffolk and State of Massachusetts, have invented certain new 5 and useful Improvements in Pneumatic-Despatch-Tube Apparatus, of which the following is a specification.

This invention relates to improvements in pneumatic despatch tube apparatus, and 10 particularly to the so-called all-sealed system, wherein a vacuum is maintained and carriers are driven therethrough by the admission of atmospheric pressure through an inlet provided for that purpose.

15 The object of my invention is to automatically open the pressure-admission inlet upon the despatching of a carrier by utilizing the flow of air caused by the opening of a valve for the insertion of the carrier.

20 In the accompanying drawings which illustrate a construction embodying my invention, Figure 1 is a diagrammatic view of a pneumatic tube system embodying this invention; Fig. 2 is an enlarged sectional 25 view showing the air inlet and timing mechanism in normal or non-operating position; Fig. 3 is a view similar to Fig. 2 showing the parts in operating position; Fig. 4 is an enlarged view partly in section showing 30 valve mechanism at the central station; Fig. 5 is a sectional view of the valve mechanism at a sub-station; Fig. 6 is an end view of Fig. 5.

Like letters of reference refer to like parts 35 throughout the several views.

Referring to Fig. 1: A is a tube for the transmission of carriers from the central station C to the sub-station S and connects at said sub-station with the ordinary delivery 40 terminal D; E is a transmission tube for the return of carriers and connects the terminal D with the terminal G. H is a vacuum tube connecting the terminal G with the drum J. K is an air-supply pipe connecting with the 45 transmission tube A at the central station and controlled by the timing mechanism L. The timing mechanism consists of the cylinder L' having an upper chamber L² connecting with the air-supply pipe K. Mounted 50 in the lower part of the cylinder L' is a piston L³ fixed to the lower end of the piston rod L⁴, the upper end of said piston rod carrying the valve L⁵ adapted to control the admission of air into the chamber L² and air-supply tube K. The chamber in the cyl-

inder L' directly above the piston is normally in communication with the vacuum in the pipe H, and connecting this chamber with the chamber below the piston L³ is a by-pass L^{5'} controlled by the timing screw 60 L⁶. L⁷ is a valve adapted to admit air into the cylinder below the piston L³. This valve is pivoted at L⁸ to the link L⁹ one end of which link L⁹ is pivoted at L¹⁰ to an extension on the cylinder L'. The opposite end 65 of the link L⁹ is pivoted to a latch bar L¹¹. A spring L¹² is adapted to hold the latch bar L¹¹ against the projection L¹³ and a spring L¹⁴ normally holds the valve L⁷ seated. Pivoted at L¹⁵ in the vacuum tube H is a 70 wing or valve L¹⁴ normally held in the position shown in Fig. 2 by a spring L¹⁵. A pawl L¹⁷ is carried by and adapted to be operated by the wing or valve L¹⁴ to engage a lip on the latch bar L¹¹. B is a valve normally closing the bell mouth or transmission tube A at the central station C. This valve is loosely pivoted on the shaft B' to which is fixed the handle B⁵ carrying the pivoted latch B⁶. On one end of the shaft B' is 75 fixed a crank connecting through the link B² and crank B³ with a valve B⁴ pivoted in the vacuum tube H. The handle B⁵ is normally held in upright position against the stop B⁷ by means of a spring around the 80 shaft B'. A similar valve F normally closes the despatching inlet in the tube E at the sub-station S, said valve being loosely pivoted on the shaft F'. A handle F⁵ fixed to the shaft F' carries the spring latch F⁶ and 85 the shaft F' is connected through a link F² and crank F³ with the valve F⁴ located in the tube E. The operation is as follows: The operator 90 in despatching a carrier from the central station C to the sub-station S lowers the handle B⁵ until the latch B⁶ engages the valve B; the handle is then raised together with the valve B and the carrier inserted 95 into the tube A; while said valve is being lifted, a flow of air is started in the tube H and acting on the wing L¹⁴ moves said wing or vane from the position shown in Fig. 2 to that shown in Fig. 3; this movement 100 of the wing through the pawl L¹⁷ raises the latch bar L¹¹ opening the valve L⁷ admitting air and destroying the vacuum maintained through the by-pass L^{5'}. The piston L³ is now lifted by the atmospheric pressure underneath to the position shown in Fig. 3 105 110

opening the valve L^5 and admitting air to the air supply pipe K causing the carrier to be driven through the transmission tube A . In the meantime, the inlet valve B has been 5 closed by reason of the latch B^6 engaging the stop B^7 and releasing said valve. The valve L^7 has also been closed by reason of the pawl L^{17} passing and releasing the latch-bar L^{11} . The air beneath the piston L^3 is 10 now gradually exhausted through the passage L^5 and the piston slowly descends by gravity until the valve $L^{5'}$ is closed and the carrier has discharged at the sub-station S . The descent of the piston L^3 is timed by 15 the screw L^6 to the interval necessary for the transmission of the carrier. When the valve $L^{5'}$ is closed shutting off the flow of air, the wing L^{14} is returned to the position shown in Fig. 2 by spring L^{15} and is now 20 ready for timing another carrier. If the operator should desire to despatch a carrier through the tube A while another carrier is in transit, the handle B^5 is lowered engaging and lifting the valve B , in the meantime 25 through the link B^2 and crank B^3 closing the valve B^4 shutting off the flow of air in the tube H and allowing the wing L^{14} to assume the normal position shown in Fig. 2, so that when the valve B is released by the 30 latch B^6 (after the carrier has been inserted in the tube A) the valve B^4 has been opened and the flow of air operates as hereinbefore described to admit air again beneath the piston L^3 and fully open the valve $L^{5'}$. 35 In returning a carrier from the sub-station S to central station C , the operation is as hereinbefore described except that the handle F^5 is used to open the valve F to permit the insertion of the carrier into tube E , the 40 valve being released and closed by the latch F^6 engaging the stop F^2 . The valve F^4 is operated by handle F^5 to cut off the flow of air in the tube H in case it is desired to despatch a carrier while another is in transit. 45 Having thus described the nature of my invention and set forth a construction embodying the same, what I claim as new and desire to secure by Letters Patent of the United States is:

50 1. In a pneumatic despatch tube system, a normally closed system comprising sending and return carrier transmission tubes communicating at the carrier discharge end of the sending tube and the carrier insertion 55 end of the return tube and with each tube provided at its opposite ends with carrier insertion and discharge valves, an air-supply pipe communicating with the carrier insertion end of the sending tube, a valve controlling 60 said air-supply pipe, an air-exhaust pipe communicating with the carrier discharge end of the return tube, a cylinder communicating at one end with said exhaust pipe and at the other end with the external air, a valve normally closing the communica-

cation of said cylinder with the external air, a piston in said cylinder connected with said valve controlling the air-supply pipe, and means, including a vane displaceable by the impact of a current of air flowing through 70 at least a part of said system, for momentarily opening the valve controlling the external air communication of said cylinder to admit outside air into the cylinder to move the piston to open the valve controlling the 75 air-supply pipe to admit external air through the air-supply pipe to the system, said vane having a tendency for movement toward a position from which it is displaced by said current of air impinging 80 thereagainst.

2. In a pneumatic despatch tube apparatus, a normally closed system comprising sending and return carrier transmission tubes communicating at the carrier discharge end of the sending tube and the carrier insertion end of the return tube and with each tube provided at its opposite ends with carrier insertion and discharge valves, an air-supply pipe communicating with the 90 carrier insertion end of the sending tube, a valve controlling said air-supply pipe, an air-exhaust pipe communicating with the carrier discharge end of the return tube, a cylinder communicating at one end with said exhaust pipe and at the other end with the external air, a valve normally closing the communication of said cylinder with the external air, a piston in said cylinder connected with said valve controlling the air-supply pipe, a spring-pressed valve in said exhaust pipe movable against the action of its spring by a fluctuation of pressure in the system, a pawl on said spring-pressed valve, and a latch-bar connected with the valve 100 controlling the external air opening of said cylinder adapted to be engaged by said pawl to move the last mentioned valve to open the cylinder to external air to move the piston to open the valve controlling the air-supply pipe to admit external air to the system.

3. In pneumatic despatch tube apparatus, a normally closed system comprising sending and return carrier transmission tubes 115 communicating at the carrier discharge end of the sending tube and the carrier insertion end of the return tube and with each tube provided at its opposite ends with carrier insertion and discharge valves, an air-supply 120 pipe communicating with the carrier insertion end of the sending tube, a valve controlling said air-supply pipe, an exhaust pipe communicating with the carrier discharge end of the return tube, a valve in said 125 air-exhaust pipe operating to close such pipe when the carrier insertion valve is opened, a cylinder communicating at one end with said exhaust pipe and at the other end with the external air, a valve normally closing 130

the communication of said cylinder with the external air, a piston in said cylinder connected with said valve controlling the air-supply pipe, and means adapted to co-act with said valve in the air-exhaust pipe and actuated by a fluctuation of pressure in the system established in part at least by said exhaust pipe closing valve for momentarily opening the valve controlling the external air communication of said cylinder to admit outside air into the cylinder to move the piston to open the valve controlling the air-supply pipe to admit external air through the air-supply pipe to the system.

4. In a pneumatic despatch tube system, a normally closed transmission tube provided at its opposite ends with carrier insertion and discharge valves, an air supply conduit communicating with the carrier insertion end of said tube, a valve controlling said air supply conduit, an air exhaust pipe, connections between said pipe and the carrier discharge end of said transmission tube, pneumatically operated mechanism for actuating said valve, a controlling valve for said mechanism, and means including a vane displaceable by the impingement thereagainst of a current of air flowing through at least a part of said system, for actuating said controlling valve for said mechanism, said vane having a tendency for movement toward a position from which it is displaced by said current of air.

5. In a pneumatic despatch tube system, a normally closed transmission tube provided at its opposite ends with carrier insertion and discharge valves, an air supply conduit communicating with the carrier insertion end of said tube, a valve controlling said air supply conduit, an air exhaust pipe, connections between said pipe and the carrier discharge end of said transmission tube, pneumatically operated mechanism for actuating said valve, a controlling valve for said mechanism, means, including a vane displaceable by the impingement thereagainst of a current of air flowing through at least a part of said system, for actuating said controlling valve for said mechanism, said vane having a tendency for movement toward a position from which it is displaced by said current of air, and means, having an operating part adjacent an insertion valve of said tube, for impeding said current of air if the latter be flowing.

6. In a pneumatic despatch tube system, a normally closed transmission tube provided at its opposite ends with carrier insertion and discharge valves, an air supply conduit communicating with the carrier insertion end of said tube, a valve controlling said air supply conduit, an air exhaust pipe, connections between said pipe and the carrier discharge end of said transmission tube, mech-

anism for actuating said valve, a controlling part for said mechanism, and means, including a member displaceable by the impingement thereagainst of a current of air flowing through at least a part of said system, for actuating said controlling part, said member having a tendency for movement toward a position from which it is displaced by said current of air.

7. In a pneumatic despatch tube system, a normally closed transmission tube provided at its opposite ends with carrier insertion and discharge valves, an air supply conduit communicating with the carrier insertion end of said tube, a valve controlling said air supply conduit, an air exhaust pipe, connections between said pipe and the carrier discharge end of said transmission tube, mechanism for actuating said valve, a controlling part for said mechanism, means, including a member displaceable by the impingement thereagainst of a current of air flowing through at least a part of said system, for actuating said controlling part, said part having a tendency for movement toward a position from which it is displaced by said current of air, and means, having an operating part adjacent an insertion valve of said tube, for impeding said current of air if the latter be flowing.

8. In a pneumatic despatch tube system, a normally closed transmission tube provided at its opposite ends with carrier insertion and discharge valves, means, including an air supply valve for establishing a carrier propelling current of air through said tube, and mechanism for controlling said air supply valve, said mechanism adapted to be actuated by a marked diminution of the flow of air in said tube followed thereafter by an increased flow of air therethrough, and means, having an operating part adjacent said insertion valve of said tube, for impeding said carrier propelling current of air, if the latter be flowing, preparatory to the actuation of said mechanism in manner aforesaid.

9. In a pneumatic despatch tube system, a normally closed transmission tube provided at its opposite ends with carrier insertion and discharge valves, means, including an air supply valve for establishing a carrier propelling current of air through said tube, and mechanism for controlling said air supply valve, said mechanism adapted to be actuated by a marked diminution of the flow of air in said tube followed thereafter by an increased flow of air therethrough, and means, having an operating part connected to said insertion valve of said tube, for impeding said carrier propelling current of air, if the latter be flowing, preparatory to the actuation of said mechanism in manner aforesaid.

10. In a pneumatic despatch tube system,

a normally closed transmission tube provided at its opposite ends with carrier insertion and discharge valves, means, including an air supply valve for establishing a carrier propelling current of air through said tube, and mechanism, for controlling said air supply valve, said mechanism adapted to be actuated by a marked diminution of the flow of air in said tube followed thereafter by an increased flow of air there-through, and means, for impeding a previously established carrier propelling current of air whenever a carrier is subsequently introduced into said system during the continuance of said previously established current.

11. In a pneumatic despatch tube system, a normally closed transmission tube provided at its opposite ends with carrier insertion and discharge valves, means, including an air supply valve for establishing a carrier propelling current of air through said tube, and mechanism, for controlling said air supply valve, said mechanism adapted to be actuated by a marked diminution of the flow of air in said tube followed thereafter by an increased flow of air there-through, and means, for impeding a previously established carrier propelling current of air whenever a carrier is subsequently introduced into said system during the continuance of said previously established current, said mechanism having provisions for normally limiting the duration of said air current to a determined interval.

12. In a pneumatic despatch tube system, a transmission tube provided at its opposite ends with carrier insertion and discharge valves, a device responsive to the pressure of air thereagainst and actuated by a change in said pressure, a main valve for controlling the flow of air through said tube, and mechanism, controlled by said device, for actuating said valve, said mechanism including a member, movement of which from a determined position starts said mechanism, and a trip connection between said device and said member for displacing said member only momentarily, when said device is operatively actuated by said change in air pressure, said trip connection thereafter permitting of the return of said member to said determined position substantially regardless of the position of said device.

13. In a pneumatic despatch tube system, a transmission tube provided at its opposite ends with carrier insertion and discharge valves, a device responsive to the pressure of air thereagainst and actuated by a change in said pressure, a main valve for controlling the flow of air through said tube, and pneumatically operated mechanism, controlled by said device, for actuating said

valve, said mechanism including a pilot valve, movement of which from a determined position starts said mechanism, and a trip connection between said device and said pilot valve for displacing said pilot valve only momentarily, when said device is operatively actuated by said change in air pressure, said trip connection thereafter permitting of the return of said pilot valve to said determined position substantially regardless of the position of said device.

14. In a pneumatic despatch tube system, a transmission tube provided at its opposite ends with carrier insertion and discharge valves, a vane responsive to the pressure of air thereagainst and actuated by a change in said pressure, a main valve for controlling the flow of air through said tube, and pneumatically operated mechanism, controlled by said vane, for actuating said valve, said mechanism including a pilot valve, movement of which from a determined position starts said mechanism, and a trip connection between said vane and said pilot valve for displacing said pilot valve only momentarily, when said vane is operatively actuated by said change in air pressure, said trip connection thereafter permitting of the return of said pilot valve to said determined position substantially regardless of the position of said vane.

15. In a pneumatic despatch tube system, a transmission tube provided at its opposite ends with carrier insertion and discharge valves, a device responsive to the pressure of air thereagainst and actuated by a change in said pressure, a main valve for controlling the flow of air through said tube, and mechanism, controlled by said device, for actuating said valve, said mechanism including a member, movement of which from a determined position starts said mechanism, and a trip connection between said device and said member for displacing said member only momentarily, when said device is operatively actuated by said change in air pressure, said trip connection thereafter permitting of the return of said member to said determined position substantially regardless of the position of said device, said device having a tendency to return substantially idly to the position from which it is displaced by said change in pressure when permitted by a reverse change in pressure of the air in contact therewith.

In testimony whereof, I have signed my name to this specification in the presence of two subscribing witnesses, this 22nd day of March A. D. 1907.

JAMES T. COWLEY.
